CENTERLESS GRINDING MACHINE

Harry Hales Asbridge, Claremont, Ashton-on-Mersey, England, assignor to The Churchill Machine Tool Company Limited, Broadheath, near Manchester, England

Application August 7, 1931, Serial No. 555,802
In Great Britain August 14, 1930

5 Claims. (Cl. 51—103)

This invention relates to centerless grinding machines of the type comprising a grinding wheel, a regulating wheel by which the rate of rotation of the workpiece is controlled, and a work-support disposed between the grinding and regulating wheels, such support being movable towards the grinding wheel under the pressure of the regulating wheel engaging the workpiece thereon.

10 The object of my present invention is to provide an improved machine of the said type adapted for the convenient, rapid and economical production of workpieces which have to be machined in two stages or operations and in which the two 15 machines portions have to be co-axial and true with one another. Bushes or tubes are examples of such workpieces, where it is required to produce a peripheral surface concentric with the hole through the bush which has been finished in a 20 prior operation (that is, to produce bushes and the like with a wall of uniform thickness). Other examples of workpieces with the two machined parts in line but of different diameter will be shown in the accompanying drawings.

25 The invention comprises the improved combinations and arrangements of parts hereinafter described and claimed.

In the accompanying explanatory drawings:—

30 Figure 1 is an end view of a centerless grinding machine having its operative parts arranged in accordance with my invention. A workpiece is shown upon the arbor at the commencement of the grinding operation.

35 Figure 2 is a view of the machine showing the workpiece at the end of the grinding operation.

Figure 3 is a plan view showing the grinding and regulating wheels and workpiece in the positions they occupy in Figure 2.

40 Figure 4 is a detail end view of the pivotally mounted work supporting bracket.

Figure 5 is a detail front view showing the stops for the handle by which the regulating wheel is moved towards and away from the grinding wheel.

45 Figure 6 is a view similar to Figure 4 showing a hollow arbor upon the work-support to receive a cylindrical extension upon the workpiece, such extension having been previously machined and being a working fit in the arbor.

50 Figure 7 is a view similar to Figure 1, and Figure 8 a view similar to Figures 4 and 6 but showing a work support in the form of a slide.

55 Figure 9 is a view similar to Figures 4, 6 and 8, and Figure 10 a plan view of Figure 9 showing a work supporting slide with means for re-

ciprocating the same in the direction of the axis of the arbor upon the slide.

Figure 11 is a view similar to Figures 4, 6, 8 and 9 but drawn to a larger scale, Figure 12 an end view similar to Figure 1 also drawn to a larger scale, and Figure 13 an end view looking from right to left of Figure 11 showing ejector mechanism for removing the workpiece from its arbor automatically. Figure 14 is a sectional view on the line 14—14 of Figure 11. 10

In Figures 1-5, *a* indicates the grinding wheel carried in suitable bearings upon the machine bed *b*; *c* indicates the regulating wheel mounted upon a slide *d* movable upon a lower slide *e* which itself is movable upon slideways upon the bed *b*. 15

f indicates the work supporting bracket which is fulcrumed about a pin *g* carried by the slide *e*. Adjustable screwed studs *h* and *i* serve as abutments or stops to limit the pivotal movements of the bracket *f* towards and away from the grinding wheel *a*. A spring *j* acting upon the bracket tends to move it so that the stop *i* is in service or the workpiece is against the regulating wheel *c*. 20

The slide *e* can be locked to the bed *b* by a locking screw *k* and the slide *d* can be locked to the slide *e* by a similar screw *l*. 25

Movement of the slide *d* can be effected in either of two ways. It can be effected by turning the screw *m* by the handles or spokes *m*¹ or by turning the handle *n* which has a threaded sleeve thereon acting as a nut for the screw *m*, such sleeve being capable only of rotary movement in the slide *d*. When the handle *n* is in use, the screw *m* is locked by a screw *r*, turned by the handle *r*¹. Stops *o* and *p* limit the movement of the handle *n*. 30

Upon the bracket *f* is secured an arbor *s* upon which each workpiece can be placed from one end. The arbor is so positioned that the axis of the workpiece to be ground is above the plane 35 containing the axes of the grinding and regulating wheels. The arbor is a working fit within the bore of the workpiece. There may be a clearance of say 5/1000ths of an inch between the arbor and the bore of the workpiece which 40 permits of easy insertion and withdrawal of the workpiece by hand. 45

The operation of the machine is as follows:—

The machine is set to bring the fulcrum pin *g* to any desired distance from the grinding wheel 50 according to the diameter of work to be operated upon by locking the slide *d* to the slide *e* and turning the screw *m*. The regulating wheel is now set so as to get its range of movement between desired limits by locking the slide *e* to the 55

bed *b*, freeing the locking screw *l* and again manipulating the screw *m*. The stops *h* and *i* are set, *i* to allow the workpiece to move clear of the grinding wheel and *h* to determine the finished diameter of the workpiece.

The stops *o* and *p* are also set, *o* to allow the regulating wheel to be moved clear of the workpiece and *p* to allow such wheel to be moved sufficiently towards the grinding wheel to enable the stop *h* to control the finished diameter of the workpiece.

The screws *k* and *r* being now locked, the operator puts the handle *n* against the stop *o* and places a piece of work *u* upon the arbor *s*. The handle *n* is now turned towards the stop *p* and moves the regulating wheel (which is being rotated at the desired speed) into contact with the workpiece whereby the latter is set in rotation and then brings the workpiece into contact with the grinding wheel to effect the desired grinding. When work is being ground with the work support in the position in which the stop *h* engages the slide *e*, grinding is being completed. The handle *n* is then moved against the stop *o*, where the spring *j* moves the bracket *f* to put the workpiece clear of the grinding wheel. It is also clear of the regulating wheel and can be conveniently and readily withdrawn by hand and a new piece inserted. The finished bush will be found to have its bore and periphery concentric so that its wall is of uniform thickness, notwithstanding the fact that the arbor is not a tight or driving fit in the bush.

Adjustment of the machine to accommodate the wear of the grinding wheel and of the regulating wheel can be readily effected by the screw *m* and by using the locking screws *k* and *l*, as will be readily appreciated.

The arbor or the part thereof which comes within the workpiece may, if desired, be free to rotate.

In Figure 6, a hollow arbor *s*¹ is secured in the bracket *f*¹ and the machined cylindrical extension *u*¹ of each workpiece *u*² is placed in such hollow arbor. The latter is so positioned that the axis of the workpiece is above the plane containing the axes of the grinding and regulating wheels. It may, however, be positioned to bring the workpiece axis below the plane containing the axes of the grinding and regulating wheels. The cylindrical extension *u*¹ has a working fit withing the bore of the arbor. There may be a clearance of 5/1000ths of an inch between the extension *u*¹ and the bore of the arbor, which permits of easy insertion and withdrawal of the workpiece by hand.

Notwithstanding that there may be a clearance of 5/1000ths of an inch between the part *u*¹ and the bore of the arbor, the surface of *u*² can be ground so that it is circular at all sections to within 1/2000th (half a thousandth) of an inch or even less and cylindrical to within the same limits. At the same time the part *u*² is co-axial or true with the extension *u*¹ to fine limits.

Instead of mounting the arbor in a pivotal pivotal work support, I may, as shown in Figures 7 and 8, mount it in a slide *f*² movable away from and towards the axes of the two wheels upon the slide *e*. The projecting part *h*¹ upon the slide *e* acts as a stop to limit the movement of the slide *f*² towards the grinding wheel. The stud *t*¹ limits the movement of the slide *f*² towards the regulating wheel, that is, away from the grinding wheel whilst the spring *j*¹ moves the slide normally towards the regulating wheel.

In the case where long pieces of work are to be operated upon, I may as shown in Figures 9 and 10 provide an intermediate slide *f*¹² between the slide *e* and the slide *f*² and provide a crank *v* and connecting rod *w* for reciprocating the slide *f*¹² and slide *f*² in the direction of the axis of the workpiece *u* and the arbor *s* carrying the same. A movable support *x* for the outer end of the arbor *s* may be provided upon an extension piece *y* from the slide *f*².

In Figures 11-13, I provide an arm *2* upon a rod *3* to push the workpiece *u* off the arbor *s* when grinding is completed. The rod *3* has a block *4* secured thereon which is engaged by the upper end of a lever *5* pivoted at *6*, the lower end of which is engaged by a pin *7* upon an arm secured upon a spindle *8* movable in the bracket *e*¹ to which the bracket *f*³ carrying the arbor is pivoted at *g*¹. A support *x*¹ for the outer end of the arbor is also moved into its out-of-service position by the block *9* upon the rod *8* when the ejector arm *2* is pushing the workpiece off the arbor. The rod is connected to the feed lever *n* in such a way that the ejector is operated to move the workpiece off the arbor when the feed lever *n* is withdrawing the regulating wheel after a workpiece has been ground to the desired size.

In Figures 11 and 12 I have shown a part *10* secured upon the pivotal work support *f*³ by the nut *11* which secures the arbor *s* thereon and into such part *10* screws a stud *12* which serves as an abutment against which bears a part *13* of the head upon which the regulating wheel *c* is mounted. The stud *12* is adjusted so that when the stop *h*² in Figure 14 which serves to limit the movement of the work support *f*³ towards the grinding wheel is in action, the part *13* of the regulating wheel head is against the stop *12* so that any twisting strain upon the workpiece is avoided. As also the handle *n* is against the stop *o* (Figure 1), there is a triple control for the end of the grinding operation to prevent pressure being applied to the workpiece after the stop *h*² has become operative. Movement of the workpiece away from the grinding wheel is effected by the spring *j*² and limited by the stop *i*². The bracket *e*¹ in this example is relatively narrow and is adapted to be secured upon a lower slide as in Figure 1, being positioned between the slide carrying the regulating wheel head and the grinding wheel head.

It will be appreciated that if the regulating wheel head were fixed or stationary and the grinding wheel were mounted upon a slide which was brought against a slide carrying the work support, the same sequence of operations would occur, as, the work support, due to the pressure of the spring *j* thereon would cause the workpiece to engage the regulating wheel first and then as the pressure of the spring was overcome, the work-piece would be engaged by the grinding wheel until the stop *h* came into action to finish the grinding operation.

Where I have referred to a spring for moving the work support towards the regulating wheel, this term is to be taken as including a weight which is the equivalent of a spring.

In the following claims, the term "arbor" is to be held to include both plug arbors and socket arbors, adapted for working engagement with the internal or external cylindrical surfaces of a workpiece respectively, and so located in the machine as to be adapted to hold the workpiece in a position such that it projects between the

grinding and regulating wheels with its axis parallel to the axes of the said wheels.

What I claim is:—

- 5 1. In centerless grinding machines, the combination of a grinding wheel and a regulating wheel both rotating in the same circular direction each having cylindrical working surfaces and disposed with their axes parallel one to the other, a work support, a work-piece carrying arbor mounted
- 10 upon said work support at such a height that the arbor axis is not in the plane containing the axes of the said grinding and regulating wheels, the said arbor receiving as a loose working fit and constituting the sole support for the workpiece
- 15 which comes between the grinding and regulating wheels and is free to rotate about the axis of the arbor irrespective of any rotation of the arbor itself and which is engaged by the said regulating wheel to move said arbor towards said
- 20 grinding wheel, a slide carrying said work support, a slide carrying said regulating wheel and movable upon the former slide, and means to position said slides relatively one to the other and to the grinding wheel.
- 25 2. In centerless grinding machines, the combination claimed in claim 1, combined with a pivotal mounting of the work support a stop to limit the movement of said work support towards said grinding wheel, and a spring to cause said
- 30 work support to move away from said grinding wheel upon withdrawal of said regulating wheel, and a second stop to limit the movement of said work support towards said regulating wheel so that said work support is clear of said grinding
- 35 and regulating wheels to facilitate removal of said work piece from said arbor.

3. For centerless grinding machines comprising in combination a grinding wheel and a regulating wheel each having cylindrical working surfaces, and disposed with their axes parallel one to the other, a regulating wheel slide and a 5 machine bed, an attachment comprising in combination a lower slide for slidably securing upon said machine bed below said regulating wheel slide, a work-support carried by said lower slide and movable towards and away from said grinding wheel and said regulating wheel, a work-piece carrying arbor non-rotatably mounted upon said work-support and adapted to receive as sole support workpieces which are free to rotate about the axis of said arbor, stops limiting the movement of said work-support in both directions and spring means tending to move said work-support in one of said directions.

4. In centerless grinding machines the combination claimed in claim 1 combined with a stop 20 to limit the movement of said work support towards said grinding wheel and an additional stop acting between the regulating wheel head and the work support whereby any twisting strain on the workpiece due to the regulating wheel 25 when the first mentioned stop prevents further movement towards the grinding wheel is avoided.

5. In centerless grinding machines, the combination claimed in claim 1 combined with a movable support carried by said work support and 30 adapted to take up one position in which it contacts with and supports said arbor at a point clear of said workpiece and another position in which it is distant from said arbor.

35

HARRY HALES ASBRIDGE.
